UNITED STATES PATENT OFFICE.

WILLIAM S. PROUDFIT, JR., OF CHICAGO, ILLINOIS.

LOOSE-LEAF BINDER.

1,037,314.

Specification of Letters Patent. Patented Sept. 3, 1912.

Application filed January 17, 1906. Serial No. 298,549.

To all whom it may concern:

Be it known that I, WILLIAM S. PROUDFIT, Jr., a citizen of the United States, residing at Chicago, in the county of Cook and State of Illinois, have invented a new and useful Loose-Leaf Binder, of which the following is a specification.

My invention relates to several details of construction in a loose leaf binder and the 10 objects of my improvements are first, to provide a leaf holding spring strip that may be flexed without kinking or breaking; second, to provide a convenient method of securing said strip to the covers of the binder; third, 15 to adjust the binder to accommodate different numbers of leaves; fourth, to conveniently lock and unlock the binder; fifth, to provide a flexible, durable and cheap construction, and other objects to become apparent from the description to follow.

From experience with binders in which the leaf holding bands were made of metallic spring strips it has been learned that after considerable use the bands would 25 sometimes become kinked at a point adjacent the binding edge of the covers and break. To prevent such kinking and breaking, I make each band of a plurality of plies or strips and curve the edges of the 30 covers between which the leaf holding bands rest. Heretofore, the fixed ends of the leaf holding bands have been secured to the covers by rivets or screws and when it was desired to change or replace the bands it 35 took considerable time and trouble, both of which objectionable features are eliminated by my invention, in which the leaf holding band is provided with a small perforation arranged to fit over a short post or lug on 40 the cover and the cover is provided with a loop or lugs on either side of said post or lug in such manner that the band, which naturally tends to be straight must be flexed by force in order to get the post or lug to 45 enter the perforation in the band and once the post is in the perforation it is prevented from leaving said position by the natural tendency of the band to lie flat and to be withdrawn from the perforation the band 50 must be flexed by force. It is of course apparent, that if the leaf holding band is provided with a series of perforations longitudinally said band can be adjusted to accommodate different numbers of leaves between the covers. Instead of clamping each of the separate adjustable ends of the

leaf holding bands as has heretofore been done, I secure the ends of all the bands to an adjustable sliding bar and have shown a set nut to clamp the same in place, although any other suitable fastening can be used without departing from the spirit of the invention.

To describe my invention so that others versed in the art to which it pertains can understand it sufficiently to enable them to make and use the same, I have illustrated it on the accompanying sheet of drawing forming a part of this specification, in which:

Figure 1, is a plan of the binder open with the leaves all removed; Fig. 2, is an enlarged sectional view taken on line 2—2 of Fig. 1; Fig. 3, is a perspective view of a leaf holding band fastening; Fig. 4, is a perspective view of a leaf holding band broken away for the purpose of illustrating, and Fig. 5, is a sectional view taken on line 5—5 of Fig. 1.

Similar reference characters refer to 80 similar parts throughout the several views.

The covers 6 and 7 are of any desirable material and are connected by the leaf holding bands 8 which are each composed preferably of two or more flat spring strips as 85 seen in Figs. 2 and 4, although they may be composed of a single member. I prefer to make these bands of thin spring steel although any other resilient material may be used. The spring bands are attached to 90 the covers in such a manner that the attached ends swing with the covers and throw the central or leaf bearing portion of the bands into a curve toward the back of the book when the covers are closed and in an 95 opposite direction when the covers are opened. By the use of such resilient bands I obtain a more sightly book and one in which the leaves will not sag from top to bottom.

The covers 6 and 7 have the metal plates 9 and 10 riveted or otherwise secured near their binding edges, which have riveted or otherwise secured to their binding edges the plates or yokes 11, which are bent away 105 from the plate to which they are secured to form space therebetween for the free passage of the leaf holding bands 8. The leaf holding bands 8 pass freely between the plates 11 and the plates 9 and 10 which construction serve as a guide for said bands. As a further guide for the bands 8 on cover 110

6 the tongues or lugs 12 are pressed up out of plate 9 high enough to permit the free passage of a band 8 underneath the same. Between the lugs 12 and their coöperating 5 plates 11 extending up a short distance from the plate 9 are the pins or lugs 13 which are preferably made integral with the plate 9 and arranged to extend into perforations 14 a plurality of which are provided in each band 8.

10 The bands 8 normally lie in a flat plane and the free ends of the lugs 13 are not in line with the spaces between plates 11 and 9 and the spaces between plates 11 and 10, 15 so that the bands 8 must be bent out of their normal position to have the lugs 13 enter the perforations 14, and when once the lugs 13 are in the perforations 14 they remain in said position until the bands 8 are flexed by 20 manual force. The perforations 14 are made considerably larger longitudinally of the bands 8 than are the lugs 13 so that the bands can shift freely for some distance longitudinally.

25 The several plies constituting the band 8 are preferably not rigidly attached to each other, being held in position by the loops in the covers under which the band passes. When the band is flexed in any direction 30 the several plies hug each other closely and adjust themselves on each other to the change of position.

I find that a band composed of several plies not rigidly attached to each other is 35 much less apt to kink or break through constant flexing and is much more pliable than a band of equal weight composed of one strip. This allows the use of a heavier and stronger band than is practical when a single spring strip is used.

An extension 15 is provided on plate 10 on which is fitted to slide a flat bar 16 by having the flanges 17 bent on the extension 18 and extending over the parallel edges of 45 extension 15. The bar 16 has secured to it the ends of the bands 8, so that by shifting the bar 16 back and forth on the plate 10 the bands 8 are moved longitudinally through the space between plates 11 and 9, 50 and the intermediate portions of said bands between the covers 6 and 7 are lengthened and shortened. As the bar 16 and the cover 7 slide freely on each other the intermediate portion of the bands 8 lying between the 55 covers 6 and 7 may also be lengthened by sliding the cover 7 back from the leaf body along the bands 8 when the leaves may be separated at any desired point and leaves added or removed. The leaves are then re- 60 bound by sliding the cover 7 along the bands 8 against the leaves and locking in this position in the manner hereinafter shown.

To secure the bar 16 in any desired position a slot 19 is provided in plate 10; the

bolt 20 extends through slot 19 and through a hole provided therefor in bar 16. The end of bolt 20 extending beyond bar 16 is threaded and a nut 21 provided with a handle is fitted thereon. The head of bolt 20 is large enough to prevent it passing through slot 19 and a portion of the same is squared and fits into said slot 19 to prevent it from turning when the nut 21 is adjusted. When nut 21 is turned loose bar 16 is free to be moved and when nut 21 is tightened the parts are clamped together and hold bar 16 against movement.

To detachably secure the ends of the bands 8 to the bar 16, the tongues or lugs 22 are punched up from the bar 16 so as to leave spaces between the lugs 22 and the body of bar 16 large enough to permit the free passage of the bands 8 therethrough, and the lugs 22 are so arranged that the bands 8 when slipped through said spaces will lie flat against the face of the bar 16 when in their normal position. The bands 8 are pliable and can be flexed upward as viewed in Fig. 2 by slight manual force so as to bring the pin or lug 23 extending from the face of bar 16 into the perforation 24 provided in band 8. It will be seen that this manner of construction for securing the bands 8 to bar 16 is about the same as that used and described to secure said bands to plate 9, and it is manipulated in the same way.

It will be understood that the lugs 12 and 22 need not necessarily extend all the way across the bands 8 as shown to accomplish their desired purpose; and other slight modifications may be made without departing from the spirit of the invention.

I prefer to use a lug or loop on each side 10 of the lug 13 to hold the band 8 in place more securely when adjusted through the perforations 14; however but one loop or lug may be employed to hold the band 8 in place when adjusted to the lug 18, as for 11 instance the lug 12 on cover 6 may be dispensed with, the yoke 11 keeping the band 8 in place when it is adjusted to the lug 13.

By increasing the number of perforations 14 or 24 at either end of the band 8 the 11 band may be adjusted on either cover to increase or decrease the intermediate portion of the band lying between the covers.

The band 8 may be secured to the bar 16 by the use of only one lug 22 and the lug 23 12 which would somewhat simplify the construction and the operation of attaching and detaching the band 8 from the bar 16.

In opening and closing the covers of the binder the greatest tendency to make a kink 12 in the bands 8 is at the binding edge of each cover or plates 9 and 10, *i. e.* at the extremities of the intermediate portion of the bands, and to prevent the bands from being bent too acutely at this point the plates 11, 13

9 and 10 have their edges curved as shown at 25, for the bands to bend over. Binding strips 29 provided with slots 30 through which the bands 8 pass freely are provided to rest between the edges of the plates 9 and 10 and the leaves of the binder.

To give a more finished appearance to the binder and to hide the metallic parts the lid 26 may be hinged at 27 to the cover and have its free end sprung under the extending lips 28 provided therefor on the plates 11.

Having thus fully described my invention, what I claim as new and desire to secure by Letters Patent of the United States is—

1. In a book binding, a leaf holding strip comprising a plurality of laterally resilient members arranged to flex in unison.

2. A leaf holding strip consisting of a plurality of laterally resilient flat springs laid together so that they may be flexed in unison.

3. In a binder, a cover and leaf holding strips each comprising a plurality of laterally resilient members arranged to flex in unison having their ends secured to said cover.

4. In a binder, a cover and leaf holding strips each comprising a plurality of laterally resilient members arranged to flex in unison having their ends detachably secured to said cover.

5. In a binder, a cover and leaf holding strips each comprising a plurality of laterally resilient members arranged to flex in unison adjustably secured to said cover.

6. In a binder, a cover and leaf holding strips each comprising a plurality of laterally resilient members arranged to flex in unison detachably secured to an adjusting means on said cover.

7. In a binder, a cover and leaf holding strips each comprising a plurality of members arranged to flex in unison detachably secured to a bar adjustably mounted on said cover.

8. In a binder, two covers and leaf holding strips, each comprising a plurality of laterally resilient members arranged to flex in unison detachably secured to both covers.

9. In a binder, two covers and laterally resilient leaf holding strips each comprising a plurality of members lying together arranged to flex in unison adjustably secured to both covers.

10. In a binder, two covers and laterally resilient leaf holding strips each comprising a plurality of members lying together arranged to flex in unison detachably secured to one cover and detachably secured to an adjusting means on the other cover.

11. In a binder, a cover, a laterally resilient leaf holding strip and means for detachably securing said strip to said cover comprising stationary lugs on said cover

arranged out of line with relation to the plane in which said strip is, so that the tendency of said strip to lie in a straight line will retain its attachment to said lugs.

12. In a binder, a cover, a laterally resilient leaf holding strip provided with a perforation, and a lug on said cover arranged to enter and be retained in said perforation by the tendency of said strip to lie in a straight line.

13. In a binder, a cover, a laterally resilient leaf holding strip provided with a perforation, and a plurality of lugs on said cover terminating alternately outside of the plane in which said strip normally tends to lie, one of said lugs being arranged to enter and be retained in said perforation.

14. In a binder, a cover, a bar adjustably mounted on said cover, laterally resilient leaf holding strips secured to said bar to have their ends lie adjacent to and swing with said cover so the portion of said strips extending away from said cover will be flexed backward and forward as the cover is closed and opened and means for securing said bar in position on said cover, comprising a threaded bolt and nut arranged to exert pressure on said bar.

15. In a binder, a cover, a laterally resilient leaf holding strip and means for detachably and adjustably securing said strip to said cover comprising a plurality of perforations in said strip and a lug on said cover arranged to enter any one of said perforations and be retained in the same by the tendency of said strip to lie in a straight line.

16. In a binder, a flat spring leaf holding strip, a cover, a metal plate forming the binding edge of said cover, a second plate secured to said first named plate bent to form a space between said two plates for the free passage of said leaf holding strip and the binding edge of said second named plate bent in a curve away from said first named plate.

17. In a binder, a cover, leaf holding strips, mechanism for adjustably securing said strips to said cover mounted on the cover, a lid hinged to said cover to cover said mechanism and stationary overhanging lugs on said cover under which the free end of said lid is removably secured.

18. In a binder, a flat spring leaf holding strip, a cover, a metal plate forming the binding edge of said cover, mechanism for adjustably securing said strip to said cover mounted on the cover, a lid hinged to said cover remote from the binding edge to cover said mechanism, a second plate secured to said first named plate bent to form space between said two plates for the free passage of said leaf holding strip, the binding edge of said second named plate bent in a curve away from said first named plate and the re-

maining edge of said second named plate provided with an overhanging lip under which the free end of said lid is removably secured.

- 5 19. In a binder, a suitable connecting member for the leaf holding strips, leaf holding strips each having one end connected to said member and the other end extending free away from said member, a cover 10 along which the leaf holding strips lie arranged to freely slide on said extension of the leaf holding strips toward and away from said member, and means comprising a bar carried by and connecting the free ends 15 of the leaf holding strips, mounted on said cover and means carried by the bar for securing the bar in any position, whereby said cover can be secured to said leaf holding strips in any desired position.
- 10 20. In a binder, two disconnected covers, laterally resilient leaf holding strips adjustably secured to said covers and means whereby one of said covers can slide along on said strips toward and away from the other 25 cover.
21. In a binder, a cover, a laterally resilient leaf holding strip and means for detachably and adjustably securing said strip to said cover, comprising a plurality of perforations in said strip, a lug on the cover arranged to extend into one of said perforations and a tongue on said cover free from said lug to normally hold the strip below the plane of the free end of said lug.
- 35 22. In a binder, a cover, a resilient leaf holding strip and an intermediate member adjustably secured to said strip and adjustably secured to said cover, said cover arranged to slide on said leaf holding strip.
- 40 23. In a binder, a cover, a bar slidably mounted on said cover, laterally resilient leaf holding strips adjustably secured to said bar and means whereby the cover can slide along on said strips.
- 45 24. In a binder, a cover, a bar slidably mounted on said cover laterally resilient leaf holding strips adjustably secured to said bar, means whereby the cover can slide along on said strips and means for locking 50 said cover to said bar in any desired position.
- 55 25. In a book binding, a leaf holding strip, consisting of a plurality of laterally resilient members laid together and arranged to flex in unison and to adjust themselves longitudinally upon each other when so flexed.
- 60 26. In a book binding, a cover, a leaf holding strip comprising a plurality of members laid together attached to have its end swing with said cover, each of said members provided with a perforation arranged so that the perforations in the several members will register when the members are laid together.
- 65 27. In a binder, a cover, a leaf holding strip comprising a plurality of laterally resilient members laid together extending out at right angles to the binding edge of said cover, and arranged to flex in unison, each of said members having perforations arranged so that the perforations in the several members will register.
- 70 28. In a binder, a cover, a resilient leaf holding strip provided with a perforation, a lug rigidly secured on said cover arranged to extend through the perforation in said strip and a second lug rigidly secured on said cover extending over said strip near said first named lug to removably hold said strip below the plane of the free end of said first named lug.
- 75 29. In a binder, a cover, a bar adjustably mounted on said cover, a leaf holding strip provided with a perforation adjustably secured to said bar and means for securing 80 said strip to said bar comprising a lug on the bar to extend through the perforation and a retaining tongue positioned to hold said strip below the plane of the free end of said lug.
- 85 30. In a binder, two covers, a bar adjustably mounted on one of said covers, resilient leaf holding strips bridging the space between the covers having one end secured to said bar on one cover and their other end 90 secured to the other cover in such manner that the opening and closing of the covers will flex the intermediate portion of said strips lying between the covers forward and backward and means for locking said bar 95 in its adjusted position, comprising a guide piece provided with a slot slidably connected to said bar and a threaded bolt and nut.
- 100 31. In a binder, two covers, a bar adjustably mounted on one of said covers laterally 105 resilient leaf holding strips bridging the space between the covers having one end secured to one of said covers and their other end secured to said bar on the other cover in such manner that the ends of said strips 110 will lie adjacent to and swing with said covers and flex the intermediate portion of said strips between the covers backward and forward when the covers are closed and opened and means for locking said bar in 115 its adjusted position, by compressing it against the cover upon which it is mounted.
- 120 32. In a loose leaf binder, the combination of two covers, a bar adjustably mounted on one of said covers, laterally resilient leaf holding strips adjustably secured to one of said covers and detachably secured to said bar on the other of said covers and means for locking said bar in its adjusted position.
- 125 33. In a loose leaf binder the combination of two covers, a bar adjustably mounted on one of said covers, laterally resilient leaf holding strips detachably secured to one of said covers and adjustably secured to said bar on the other of said covers and means 130

for locking said bar in its adjusted position.

34. In a loose leaf binder the combination of a pair of swinging covers, a bar adjustably mounted on one of said covers guided to be moved toward and away from the binding edge of said cover, resilient leaf holding strips having one end attached to said bar and guided to run along said cover, over the binding edge thereof, to the binding edge of and along the other of said covers to which they are attached, the ends of said strips arranged to swing with said covers and to flex the intermediate portion thereof lying between the covers and means for moving said bar back and forth and locking it in any desired position.
35. In a binder, a cover, leaf holding strips each having one end connected to said cover and the other end extending free away from said cover, a second cover along on which the leaf holding strips lie arranged to freely slide on said extensions of the leaf holding strips toward and away from said first named cover and means whereby said second named cover can be secured to said leaf holding strips in any desired position comprising a cross bar connecting the free ends of said leaf holding strips and a bar on which said cross bar is slidably mounted, secured to said second named cover.
36. In a binder, the combination with the

covers, of leaf holding strips, of a cross bar to which said strips are secured arranged to be adjusted in one of said covers and 35 clamping means to be clamped against and released from the bar for securing said bar in its adjusted position so that said cross bar may be moved freely in said cover when the clamping means is in a released position. 40

37. In a binder, a cover, leaf holding strips, each having one end connected to said cover and the other end extending free away from said cover, a second cover along on which the leaf holding strips lie arranged 45 to freely slide on said extension of the leaf holding strips toward and away from said first named cover and means comprising a bar connecting and carried by the free ends of the leaf holding strips, mounted to slide 50 freely on said second named cover, and means carried by the bar for securing the bar in any position whereby said second named cover can be secured to said leaf holding strips in any desired position.

In testimony whereof I have signed my name to this specification in presence of two subscribing witnesses this 10th day of January 1906 at Chicago, Illinois.
